MACHINE FOR CLINCHING A HOOP CONNECTING MEMBER AND THE LIKE

Harry Guthrie Bell, Jacob Douglas Gay, Jr., and Keith Gilmore Shaffer, Paris, Ky., assignors to The Gay-Bell Corporation, Paris, Ky., a corporation of Kentucky

Application June 6, 1956, Serial No. 589,805

11 Claims. (Cl. 1—210)

Our invention resides in the addition of improvements to the basic clinching machine shown, claimed and described in Patent No. 2,484,398 which issued on October 11, 1949, to Harry Guthrie Bell and Jacob Douglas Gay, Jr.

An important object of our invention is to provide means for positively maintaining the eye of a hinged connecting member while the leaves of such connecting member are clamped to the work.

A further object of our invention is to provide alignment means for the eye of the hinged connecting member which may be readily adapted to the basic structure shown in the aforementioned patent.

Another object of our invention is to provide alignment means of the type described which are positive in action and relatively simple to install.

While the clinching machine of the aforementioned patent proved to be satisfactory in operation there was a fault which did develop. In spite of the provision of the seat to receive the eye of the hinged connecting member while the leaves were moved by the clinching anvil, it still sometimes developed that this eye would be crushed slightly so as to give it a sort of egg-shape. When the eye was thus distorted the pins by which the hogshead or barrel sections were to be maintained, these pins being designed to pass through such eyes, would not pass through the distorted eyes. This meant either that additional work, largely hand work, had to be performed to align and reshape the eyes or that added inspection had to be utilized in order to discover such deformations before the barrel or hogshead panel moved too far along the production line. In any event extra work and increased scrap resulted.

An important object of our invention, therefore, is to provide means to prevent the deformation of the eye portion of the hinged connecting members utilized in assembling hogsheads so as to decrease the amount of time involved in assembling hogsheads and so as also to decrease the amount of scrap.

These and other objects of our invention will become more apparent to those skilled in the art during the course of the following description and with reference to the accompanying drawings, in which drawings like numerals are employed to designate like parts and in which:

Figure 1 is a side elevation of a clinching machine incorporating the instant invention,

Figure 2 is an enlarged section taken on the line 2—2 of Figure 1,

Figure 3 is a fragmentary side elevation of a portion of the mechanism at one stage of the clinching operation,

Figure 4 is an enlarged section taken on the line 4—4 of Figure 3 but showing certain of the parts after further actuation of the machine,

Figure 5 is a perspective view of a seat provided for the eye of the hinged connecting member during the clinching operation,

Figure 6 is a perspective view of the hinged connecting

2

member on which the clinching machine of this invention is designed to operate,

Figure 7 is a fragmentary plan view showing the position of the connecting member and alignment means at the start of the clinching operation,

Figure 8 is a section taken on the line 8—8 of Figure 7, and

Figure 9 is a fragmentary section showing an alternative way of mounting the alignment means.

10 In the description to follow we will not unduly elaborate on those portions of the disclosed structure which are old and described in considerable detail in Patent No. 2,484,398. Only so much of this old structure as is necessary to the ready understanding of the instant invention will be described in any detail.

The machine of our invention is designed to fasten properly a hinged connecting member generally indicated at 30 to a stave 39 having a hoop 8 thereon. This connecting member 30 has an upper leaf 31, a lower leaf 32 and an eye or pintle aperture 33. The upper leaf 31 has a large prong 34 and a plurality of prongs 35 while the lower leaf 32 has a series of apertures to receive the just-named prongs. The end of the hoop 8 is spaced from the stave 39 a distance just sufficient to receive the lower leaf 32.

20 It is contemplated that this lower leaf 32 of the connecting member 30 will be placed on the stave beneath the hoop end 8. With the connecting member 30 thus properly positioned the clinching machine will be moved into operative position and the upper leaf 31 clinched against the hoop 8. As this occurs the prong 34 passes through an aperture in the hoop 8 and an aperture in the lower leaf 32 after which it is clinched against the lower surface of the stave 39. The short prongs 35 will pass through corresponding apertures in the hoop 8 and lower leaf 32 35 but are not intended to pass all the way through the stave 39.

Our invention resides in the means for preserving accurately the shape of the pintle aperture 33 of the connecting member 30 during the just described clinching operation.

40 As perhaps best seen in Figure 1 the clinching machine to which this invention is specifically directed comprises a base 1 which is slidable to and from the conveyor which carries the stave 39 and hoop 8. On the base 1 are upstanding supports 10 which carry an operating cylinder 11 in which there is a piston having a piston rod 12. Although the cylinder 11 has been illustrated as being pneumatic it will readily appear that the machine may be driven hydraulically, mechanically, electrically or in numerous other ways.

45 Fastened to the end of the piston rod 12 is a yoke 17. Projecting downwardly from the yoke 17 are three connecting rods 18, 19 and 20. The clinching ram 21 is pivotally connected to the rod 18 and to a casting 23 which is slidable in ways provided in a portion 27 of the machine.

50 Fixed to the rod 19 is a member 25 which actuates means for locking the casting 23 in proper position after the lower end thereof seats on the frame portion 27a. When the casting 23 is so locked it serves as a fulcrum base for the clinching ram 21. Such locking means comprises a latch plate 23a slidable in casting 23. Member 25 passes through a hole in the plate 23a and has a cam bearing surface 25a.

55 When the casting 23 is so locked it serves as a fulcrum base for the clinching ram 21. Such locking means comprises a latch plate 23a slidable in casting 23. Member 25 passes through a hole in the plate 23a and has a cam bearing surface 25a. When the casting 23 seats on the frame 27a further movement of the member 25 causes the portion 25a to shift the plate 23a into the notch 27b whereby to lock the casting. This is illustrated in Figures 1 and 2.

60 A plunger 28 is fixed to the rod 20 and so arranged as to actuate a prong-clinching anvil in the manner described in the Patent 2,484,398 and not here shown in detail.

Also positioned on the frame member 27a is a seat 38 to receive the eye or pintle aperture 33 of the connecting member 30 when the machine is moved into clinching position.

The operation of this much of the machine is as follows. The machine is positioned so that the eye 33 rests within the seat 38. The piston rod 12 is then moved downwardly as are also the rods 18, 19 and 20. The casting 23 will seat against the frame member 27a and be locked in position as described. The clinching ram 21 will engage the upper leaf 31 and force it against the hoop 8 while at the same time driving the prong 34 through apertures in the hoop 8 and lower leaf 32 and completely through the stave 39 whereupon the end of this prong will be wiped flat against the stave bottom 39 by means of the prong clinching anvil which is actuated by the cam plunger 28 fastened to the rod 20. Following this the valve controlling the cylinder 11 will be reversed and the parts will return to the position shown in Figure 1.

This invention comprises the following improvements added to the old, basic structure just described. A pair of levers 50 is pivoted at 51 on the casting 23. A spring 52 centered on pins 53 normally urges the lower ends of the levers 50 away from one another.

The lower end of each of the levers 50 carries a pin or pintle 54 having an enlarged head 55. These pins are slideable in enlarged apertures 56 provided in the lower ends of the levers 50. These pins are also slideable in apertures formed in a lower flanged portion of the casting 23. In addition these pins engage and are slideable in apertures formed in the lower end of the anvil 21. This end of the anvil 21 has a clearance 21a adapted to receive the seat 38 and pintle aperture 33 located therein. By the arrangement just described it will be apparent that the pivoted connection between the anvil 21 and casting 23 is effected by means of the pins 54. An alternative arrangement is shown in Figure 9 wherein the pivoted connection between the members 21 and 23 is effected by a double headed bushing 57 having a single aperture to receive the pin 54. This might give a somewhat more stable construction.

The normal position of the parts prior to the clinching operation is that illustrated in Figure 2. It will be observed that the lower ends of the levers 50 are in their spread-apart position. In this position the inner ends of the pins 54 have just barely passed through the anvil flanges to the clearance area 21a. It will be understood that when the casting 23 seats on the frame member 27a these pins 54 will be exactly aligned with the pintle aperture 33 of the connecting member 30 abutting the seat 38. The clearance area 21a is sufficiently large to receive the seat 38 and eye 33 between the pins 54 when in the position shown in Figure 2.

Carried on the lower ends of the levers 50 are blocks 58 having adjustable set screws 59 designed to abut the enlarged heads 55 of the pins 54. These screws 59 may regulate the depths to which the pins 54 penetrate the area 21a when the levers 50 are moved against the action of the spring 52 as will now be described. The enlarged apertures 56, of course, permit horizontal sliding movement of the pins 54 while the levers 50 move through an arcuate path when pivoted about the points 51 while the enlarged heads 55 insure that the pins will be withdrawn when the levers are spread apart under action of the spring 52.

Fixed on the cam rod 25 is a cam 60. This cam rod 25 slides within the casting 23 as described in the said Patent 2,484,398. After the casting 23 has bottomed on the frame portion 27a continued downward movement of the yoke 17 will result in similar movement of the cam rod 25. This in turn will bring the cam 60 into contact with the cam surfaces 61 of the upper portions of the levers 50. The cam 60 will spread apart the upper portions of the levers 50 with the result that the lower portions thereof will be moved towards one another.

against the action of the spring 52. The screws 59 will engage the heads 55 of the pins 54 so that continued inward movement of the lower ends of the levers 50 will result in the pins 54 being moved towards one another.

The apparatus is so arranged that the pins 54 will move to the position shown in Figure 4, wherein they lie within the pintle aperture 33 of the connecting member 30, prior to the final clinching operations so that this pintle aperture or eye 33 is fully supported at the time of the greatest pressures are applied to effect clinching of the member 30. These pins 54 are of a size sufficient to maintain the desired shape of the aperture 33.

It is believed that the operation of this invention has been clearly set forth above in sufficient detail for a ready understanding of it and, therefore, it will not be described further at this time. It will be understood, however, that although we have described our invention as embodied in certain particular structures and arrangements, we do not intend to be limited to these structures and arrangements except insofar as they are specifically set forth in the subjoined claims.

Having thus described our invention, what we claim as new and what we desire to protect by United States Letters Patent is:

1. In a clinching machine for forcing a pair of joined leaf elements towards one another while maintaining a pintle aperture therebetween and comprising a clinching anvil, a slideable casting, said anvil being pivoted to said casting, a frame rest, a seat on said rest to receive said pintle aperture, and means to move said casting against said rest and said anvil against a said leaf element, the improvement which comprises: a pair of levers pivoted to said casting intermediate their ends, a pin slideable in the lower end of each of said levers and means to move the lower ends of said levers towards one another so as to move said pins into said pintle aperture while said anvil is moved against a said leaf element.

2. The improved machine of claim 1 in which said last mentioned means comprises a cam member and means to engage said cam member between the upper ends of said levers.

3. The improved machine of claim 1 in which said anvil is pivoted to said casting by said pins, said anvil having a clearance area to receive said seat, and said pins before actuation of said last mentioned means being spaced to permit reception of said seat in said clearance area.

4. The improved machine of claim 1 including spring means to urge the lower ends of said levers away from one another.

5. The improved machine of claim 1 in which said pins are mounted in enlarged apertures in said levers for rocking and sliding movement therein, and other means on said levers engaging said pins to regulate their penetration into said pintle aperture.

6. In a clinching mechanism including a slideable casting, a movable anvil pivoted to said casting, a frame rest, a work seat on said rest, and common means to move said anvil and said casting, said casting bottoming on said rest and said anvil straddling said seat, the improvement which comprises: a pair of levers pivoted to said casting intermediate their ends, a pin slideable in the lower end of each of said levers and aligned with said seat when said casting bottoms on said rest, spring means urging the lower ends of said levers apart, and cam means to engage the upper ends of said levers so as to move the lower ends of said levers towards one another against the action of said spring means, whereby said pins are moved towards one another through said seat.

7. The mechanism of claim 6 including adjustable abutments on said levers and engaging the outer ends of said pins.

8. The mechanism of claim 6 in which there is a pair

of bushings between said anvil and said casting, each said pin being slidable in a said bushing.

9. A clinching machine for closing the leaves of a hoop connecting member and the like while preserving the shape of a pintle aperture formed at the juncture of the leaves, which comprises: a frame rest, a seat on said rest to receive the pintle aperture of said connecting member, a sliding member adapted to bottom on said rest, an anvil pivoted to said sliding member and adapted to engage a said leaf, said anvil having a portion to receive said seat, and pins movable into said pintle aperture during engagement of a said leaf by said anvil.

10. The machine of claim 9 in which there is a pair of said pins, a pair of levers pivoted in said machine, each pin being mounted in a said lever, and means to actuate said levers so as to cause said pins to enter said pintle aperture.

11. The machine of claim 10 in which said pins are slidable in said sliding member and said anvil, said pins extending to the seat receiving portion of said anvil, said pins being loosely mounted in said levers, and adjustable abutments on said levers engaging said pins.
